UNITED STATES PATENT OFFICE.

AUSTIN W. MORRILL, OF LOS ANGELES, CALIFORNIA.

FUMIGATING-COVER.

1,372,974.

Specification of Letters Patent.

Patented Mar. 29, 1921.

Application filed January 3, 1920. Serial No. 349,317.

To all whom it may concern:

Be it known that I, AUSTIN W. MORRILL, a citizen of the United States, residing at Los Angeles, Los Angeles county, State of California, have invented a certain new and useful Improvement in Fumigating-Covers, of which the following is a full, clear, and exact description.

My invention relates to an improvement 10 in the box type of fumigating cover for use in fumigating trees, more particularly trees of small and medium sizes, and has for its object the provision of a gas-tight or practically gas-tight cover of known cubical capacity, which can be more readily changed 15 from one tree to another and can be made ready for the treatment with less time and effort than box style covers heretofore in use.

The following is a description of an embodiment of my invention, reference being had to the accompanying drawings, in which,

Figure 1 represents an end view of my cover, the two ends being preferably the 25 same in construction and appearance;

Fig. 1^a is a detail;

Fig. 2 is a plan view of a portion of the cover;

Fig. 3 is a side elevation of a portion of 30 the cover with the curtain extended in abnormal position to show the connection between the edges thereof and the sides of the body of the cover;

Fig. 4 is a vertical section on the line 4—4, 35 Fig. 2, with the curtain in normal position; and

Fig. 5 is a perspective of the framework of the cover.

Referring more particularly to the drawing, the device is of box type and composed of two vertical sides 1—1' connected by a top 2 forming a tunnel-like body portion, and curtains 3 at each end, whose edges are joined by webs 4 extending from the edges 45 5 of the curtain 3 to the edges 6 of the side portions 1—1'. The sides and top of the tunnel portion are provided with the open ended framework shown in Fig. 5, consisting of uprights 7 connected by cross-pieces 50 8, 8' and 9, the side members having braces 10. The ends may be provided with braces 10' located at their upper portions so as not to interfere with the open ends of the frame. The tunnel portion with the curtains thus 55 forms a box-like container whose capacity can be determined with approximate accuracy.

Connected to the uprights 7 are two bars 11, the ends of which constitute handles so that the tunnel portion with its end closures can be easily lifted by having one man 60 at each handle. This frame work is provided at its four upper corners with pulleys 12 and at points intermediate of its sides with double pulleys 13. Before or after these pulleys 12 and 13 are put in place, the 65 top and two opposite sides of the framework are covered with canvas or other material which will be impervious to the fumigating gases, the same being preferably permanently secured at its edges to the frame. 70 The ends of the tunnel-like structure thus formed are provided with curtains 3, the tops of which are secured to the top edges of the tunnel and the side edges 5 of which are connected to the vertical edges 6 of the 75 ends of the tunnel by webs 4, as heretofore described. The curtains are provided with guide-rings 14 through which pass ropes 15 connected at their lower ends 16 to a wooden bar 17, which is connected to the lower end 80 of the curtain 3. These ropes 15 pass upward around the pulleys 12 and over the respective pulleys of the double pulleys 13 and the ends are then brought down and secured to cleats 18 upon the bars 11. 85

The webs 4 are of such shape and dimensions that the length of the lower edge of the web connecting the lower end of the side 1 with the lower end of the curtain 3 is approximately as long, if not longer, than 90 the height of the sides 1. This enables the curtain 3 to be raised vertically by means of the ropes 15 to substantially the top of the tunnel portion of the cover, and yet when the curtain is lowered all openings in 95 the box-like cover will be closed except the opening between the bottom of the sides and curtain and the ground, since the free edges of the cover will be adjacent to the ground, thus providing a box cover which will retain to a high degree all fumigating gases introduced or formed therein.

The web 4 is shown in normal position in Fig. 4 when the curtain is lowered. The position of the curtain in Fig. 3 is abnormal, 105 being pulled out to show the connections between the web and the edges of the curtain and body portion.

In the use of this device as thus described, one of the curtains 3 is first raised and the 110 device is then moved over the tree to be fumigated. The raised curtain is then low-

ered and the fumigating charge introduced. Because the device is non-collapsible and maintains its shape, its cubic capacity can be closely calculated and the proper amount 5 of fumigating charge can be determined and introduced. After the tree has been fumigated, the device can then be easily moved to another tree by raising the lowered curtain. If the trees are in a row, both curtains 10 are raised, whereupon the device by a movement in one direction can be moved away from one tree to the next succeeding tree of the same row, whereupon after lowering both curtains the fumigating process 15 can be repeated, so that any number of trees in a given row can be treated without reversing or even turning the device through any angle.

In order to adapt the device for use with 20 trees of different heights, I provide extensions 19 which can be secured by bolts 20 to the uprights 7 of the frame in any one of a plurality of positions, thus raising the frame a corresponding amount. In order 25 that the side walls of the tunnel may be extended accordingly, I provide the side portions with integral extensions 21 which can be drawn down so as to reach the ground when the legs 19 are attached. These 30 extensions when the legs are removed are preferably held in folded position by canvas strips 22 attached to the side frames. The lower ends of the webs 4 extend to the 35 lower ends of these sections and are secured thereto, as shown in dotted lines in Fig. 3, and the curtains 5 are of such length that when they are fully lowered they will come in contact with the ground, even when the frame is supported by the supplemental legs 40 19. The fumigating cover is thus a tight box-like cover, except for the opening adjacent to the ground, both in its extended and shortened condition.

In order to support the upper bend of 45 the side folds 21, I preferably secure to the inside of the canvas at that point a strip of scantling 23, which carries buttons 24 which are engaged by the canvas strips 22, as shown in enlarged detail in Fig. 1^a.

50 From the foregoing it will be seen that the cover above described is practically a gas-tight box-like cover; that it also can be made of a known cubical capacity and that it can be readily changed from one tree to another and can quickly and easily be made ready for treatment, so that the above named objects of my invention are accomplished.

I prefer to have the frame open at both 60 ends so as to be U-shaped as shown, and to have a curtain at each end so as to be able to treat rows of trees by moving the device in one direction only, as above described.

65 While I prefer to use the webs perma-

nently connecting the edges of the curtains to the vertical edges of the body portion of the cover, these may in some instances be omitted, provided other means are used for securing those edges so as to prevent 70 the escape of gas between those edges when the device is in use.

As will be evident to those skilled in the art, my invention permits of various modifications without departing from the spirit 75 thereof or the scope of the appended claims.

What I claim is:

1. In a fumigating device, the combination 80 of a frame having an open end, a cover carried by said frame and approximately conforming to the shape thereof so as to form a device of the box type, said cover being permanently secured to the two opposite sides of said frame, and means carried by said frame for raising a portion 85 of the cover at said open end to permit the placing of said frame about the object to be fumigated, the free edges of said cover when in use being adjacent to the ground. 90

2. In a box type fumigating device, the combination with a body portion having a supporting frame open at one end and a cover for the other end and the top and sides of said frame, of a curtain for said open end of said frame, and means for preventing the escape of gas when the device is in use between the sides of said curtain and the upwardly extending edges of the sides of said body portion which are 100 adjacent to said curtain when in lowered position, and means for raising and lowering said curtain. 95

3. In a box type fumigating device, the combination with a body portion having 105 a supporting frame open at one end and a cover for the other end and the top and sides of said frame, of a curtain for said open end of said frame, and webs connecting the edges of said curtain with the upwardly extending edges of the sides of said body portion which are adjacent to said curtain when in lowered position, and means for raising and lowering said curtain. 110

4. In a fumigating device, the combination 115 of a U-shaped frame open at both ends, a cover having its free edges adapted to extend substantially to the ground on all sides of said frame and conforming approximately to the shape of said frame, said cover being permanently secured to the two opposite sides of said frame, and means carried by said frame for raising from the ground the portions of said cover at said ends of said U-shaped frame. 120

5. In a fumigating device, the combination 125 of a tunnel-like body portion having a supporting frame, curtains covering the ends of said tunnel-like portion and webs connecting the edges of said curtains with the 130

upwardly extending edges of the openings of the tunnel-like portion, and means for raising said curtains.

6. In a box type fumigating device, the combination with a body portion having a supporting frame open at one end and a cover for the other end and the top and sides of said frame, of a curtain for said open end of said frame, and webs connecting the edges of said curtain with the up-

wardly extending edges of the sides of said body portion which are adjacent to said curtain when in lowered position, means for raising and lowering said curtain, and means for downwardly extending the sides 15 of said frame and said covering so as to vary the height of said fumigating device, said curtain having a length corresponding to said extended height.

AUSTIN W. MORRILL.
